Primary Examiner — Natasha Vujcic(74) *Attorney, Agent, or Firm* — Cooley LLP; Nathan W. Poulsen(57) **CLAIM**

The ornamental design for a unified casting light module, as shown and described.

DESCRIPTION

FIG. 1 is a front right perspective view of the new design for a unified casting light module, the front left perspective being a reverse mirror image thereof; and,

FIG. 2 is a front view of the new design for a unified casting light module.

The portions or features of the unified casting light module not shown in the drawings form no part of the claimed design. The broken lines in the drawings form no part of the claimed design.
